HARRY A. GREENHOLT, OF CHICAGO, ILLINOIS, ASSIGNOR TO NATIONAL BISCUIT COMPANY, OF NEW YORK, N. Y., A CORPORATION OF NEW JERSEY

FACING MACHINE

Application filed August 16, 1926. Serial No. 129,388.

This invention relates to a facing machine of improved construction.

While the invention may be utilized in numerous different associations, it is intended primarily to be employed in connection with the baking industry, and when so used, will accurately, rapidly and economically face crackers or cookies having dissimilar opposite faces and arrange the same in row formation.

By means of the present invention a machine is provided which will occupy a relatively small amount of space, the parts of which will be relatively few in number and simple in construction and which may be readily assembled to provide a machine operating efficiently over long periods of time, with freedom from mechanical difficulty, and in which the parts may be adjusted to permit the machine to face and arrange different sizes and shapes of articles.

Other objects of the invention will in part be obvious and will in part appear hereinafter.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawing, in which:

Figure 1 is a partly fragmentary sectional side view of one form of machine embodying the improved construction of the present invention;

Figs. 2 and 3 are transverse sectional views taken along the lines 2—2 and 3—3 of Fig. 1 and in the direction of the arrows indicated in that figure;

Fig. 4 is an enlarged rear end view of the machine as shown in Fig. 1;

Fig. 5 is a diagrammatic perspective view of a portion of a roller-supported belt; and

Fig. 6 is a sectional view of the mechanism shown in Fig. 5.

In these several views the numeral 10 indi-

cates a plate or deck providing a support, and the forward and rear edges of which, if desired, may be extended downwardly as at 11. Rollers 12 and 13 are mounted upon shafts 14 adjacent the forward and rear ends of the deck and have the uppermost portion of their peripheries extending into the plane of the upper deck level. Passing around these rollers and over the upper face of the deck is a facing conveyor, preferably, and as exemplified, comprising a pair of adjacently disposed belts 15 of any suitable material; and tensioning rollers 16 may be provided below the deck in order to maintain the bodies of the belts free from slack. As indicated in Fig. 4, any desired number of conveyors, such as pairs of belts 15, may be employed, so as to provide laterally disposed article-receiving means.

Mounted upon the plate 10 are tilting-plates 17 corresponding in number to the number of belts employed, these plates preferably being bowed throughout their entire length to provide end portions lying substantially parallel to the plane of the deck and central portions extending at a material angle thereto, for example, 80 degrees, as shown. Supporting members 18 are affixed to the rear faces of these plates and have their lower ends pivotally secured as at 19 to brackets 20, which latter are adjustable transversely with respect to the deck by means of bolt-and-slot connections 21. At this time it will be understood that the tilting-plates 17 preferably are formed of relatively thin stock and are sufficiently flexible for the arms 18 to be swung to vary the angular relationship of the plates with respect to the deck without interfering with the parallel disposition of the plate ends with respect to such deck. As will be seen, the plates are arranged in pairs, and pairs of belts bear against the opposed faces thereof. It is obvious that due to the adjustment provided by the bolt-and-slot connections 21 the distance between the belts may be varied to accommodate different sizes

of articles; it being understood, however, that at the point of maximum tilting the inner lower edges of the pair of belts in each instance preferably are immediately adjacent each other.

In the form of machine shown in Figs. 5 and 6, the plates 17 and associated structures are dispensed with, spaced rollers 22 being substituted therefor, these rollers efficiently supporting the belts in proper angular relationship with respect to the deck. The rollers are mounted by utilizing brackets 23, between the arms of which shafts 24 are yieldingly supported as at 25, a roller being carried by each of these shafts. Adjustable mounting member 26 similar to the mounting members 20 are secured to the deck, and these mounting members as at 27 pivotally support the brackets. The angle between the belts 15 and deck 10 increases gradually from zero degrees at the entrance end for about two-thirds of the length of the deck, where it reaches a maximum, which, as exemplified, is approximately eighty degrees, and then decreases to zero degrees again where the belts lie in the plane of the deck. Conversely the angle between adjacent belts of a pair is a maximum of 180° at each end of their upper surfaces, in the exemplified apparatus, and a minimum of approximately 20° at the point of maximum tilt. These angles, of course, are variable, and adjustment of the same may be suitably accomplished as by the adjustment of supports 18 or 22. In the form of the invention shown in Figs. 1 to 3, the tilting plates 17, which extend substantially the full length of the deck, together with the belts 15, form in the upper run of the belts a V or trough-shaped section, the belts 15 being driven by the driving roller 12 to carry the articles along the trough. In the modified form shown in Figs. 5 and 6, the supporting rollers 22 and belts 15 cooperate to form in the upper run of the belts the V-shaped trough section along which the belts, driven from the roller 12, carry the articles.

It will be appreciated that a machine of this nature, when utilized by the baking industry, may be placed to the rear of one of different types of machines. In the present exemplification a hopper 28 has been shown, from which the articles are discharged onto a conveyor 29, upon which they lie promiscuously with different faces of adjacent articles uppermost. The conveyor 29 discharges onto the series of belts 15, and the latter may be driven in any suitable manner, as, for example, at 30, to have a rate of travel corresponding to the speed of movement of the conveyor 29. The crackers or other articles will enter the troughs or grooves provided by the two-cooperating belts of each pair, and thus these articles will be disposed in row formation. Incident to the increasingly greater inclination of any given area of the belt bodies as the latter traverse the length of the deck, the crackers will assume an increasingly perpendicular position in their passage lengthwise of the machine, and the inclination of the articles will be continued until

they pass the point of maximum inclination of the belts, subsequently to which they will again gradually assume a position at which their bodies extend in a plane parallel to the face of the deck. At this point they are transferred by means of rollers 31, or by other suitable mechanism, from the upper faces of the belts to a conveyor 32, these latter elements being driven in any suitable manner, and the conveyor, if desired, leading to a packaging machine.

The crackers, upon being discharged from the conveyor 29 will come to lie upon the belts 15, and those crackers which are disposed upon these belts with their flat faces lowermost will maintain their positions throughout the entire travel through the machine. However, considering the passage of an article which lies with its convex face or beveled edge portions downwardly, it will be appreciated that this article initially will be inclined with its body resting upon one belt and its lower edge in contact with the adjacent belt of a pair. As the angularity between the pair of belts decreases, the last-named belt will exert pressure upon the cracker edge, while the first named belt will exert pressure upon the rounded face of the cracker at some distance inwardly from its edge, which produces a turning moment or couple to tilt the cracker about the edge that is in contact with the second named belt, resulting in a major portion of the body thereof being moved out of contact with the face of the first belt, and the continued movement of the parts will result in the article being tilted by cooperation with the belts until it moves through a plane perpendicular to the plane of the deck, and finally, beyond the same, whereupon it will rest with its flat face against the second belt, as clearly shown in Figs. 2 and 3. Thus, the belts continuing to move, the article which was disposed upon the surface provided by the belts with its flat face uppermost, at the rear end of the machine will have its flat face extending downwardly so that all articles at this point, in addition to being disposed in row formation, will be faced similarly with virtually no likelihood of "accidentals".

From the foregoing it will be appreciated that the objects of this invention have been accomplished, and since certain changes may be made in the above construction, and different embodiments of the invention could be made, without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described and all statements of

the scope of the invention which as a matter of language might be said to fall therebetween.

Having described my invention, what I claim as new and desire to secure by Letters Patent is:

1. A facing machine for an article having a substantially flat face and sharp edge on one side and a receding edge on the other side, including a pair of driven belts having adjacent edges spaced apart less than the thickness of the articles being faced, guide means for said belts intermediate their ends disposed to tilt opposed portions of said belts to form a V of sufficient acuteness that one side of the V will exert pressure on the sharp edge of the article being faced and the other side of the V will exert pressure on the receding side of the article inward from its extreme edge, whereby a turning moment will be produced to turn the flat face of the article against one of the belts.

2. A facing machine for articles having sharp edges on one side and rounded edges on the other side comprising a conveyor having a part of its run displaced to provide a V trough shaped section, the slope of the sides of the trough increasing from each end toward the center to provide a V of sufficient acuteness that one side of the trough will exert pressure on the edge of the article and the opposite side will exert pressure on the rounded side of the article distant from the edge, whereby to produce a turning moment to tilt the flat side of the article against one side of the trough, means for supplying articles to one end of the trough, and means to cause travel of the conveyor to move the articles along the trough.

3. A facing machine for articles having a substantially flat face and having receding-edge portions, including a pair of driven belts having one edge of each adjacent the other and having their faces approximately horizontal at the beginning of their upper traverse, and guide means for said belts disposed to cause opposed unit surfaces of the belts to form an acute angle and subsequently to assume an increasing angle, with respect to each other during said upper traverse as the belts are driven, said belts being adapted when they are at a minimum angle to grip the edges of articles carried thereby to tilt and face such articles as are carried flat face upward on either of said belts.

4. A facing machine for articles having a substantially flat face on one side and a receding edge on the other side including a deck, a pair of driven belts arranged with their upper traverses above said deck and adjacent thereto, the space between the adjacent edges of said belts being less than the thickness of the articles being faced, guide means for said upper traverses disposed to tilt the belts toward each other to

cause them to assume a decreasing angle with respect to each other, including an angle of sufficient acuteness that the belts near their adjacent edges will exert pressure in different planes on the articles to be faced and cause their flat faces to lie against one of the belts, means for increasing the angle between the belts to substantially 180° whereby the articles will lie on the belts with their flat faces down, and means for driving the belts.

5. A facing machine for articles having a substantially flat face and having receding-edge portions, including a pair of driven belts having one edge of each adjacent the other, and guide means for said belts disposed to cause opposed unit surfaces of the belts to assume a decreasing angle including an acute angle, and subsequently to assume an increasing angle, with respect to each other as the belts are driven; certain of said guide means being adjustable to vary the angle of the belt surfaces as they pass thereover, said belts being adapted when they are at a minimum angle to grip the edges of articles carried thereby to tilt and face such articles as are carried flat face upward on either of said belts.

6. A facing machine for articles having a substantially flat face and having receding-edge portions, including a pair of driven belts having one edge of each adjacent the other, and guide means for said belts disposed to cause opposed unit surfaces of each to assume a decreasing angle, and subsequently to assume an increasing angle, with respect to each other as the belts are driven; at least certain of said guide means comprising adjustably-mounted rollers to vary the angle of the belt surfaces as they pass thereover, whereby said belts will grip the edges of articles carried thereby to tilt and face such articles as are carried flat face upward on either of said belts.

7. A facing machine including a deck, a pair of belts arranged with their upper traverse substantially parallel to and above the deck, with their inner edges substantially in contact and with the beginning of their upper traverse substantially in the plane of the deck, means for driving said belts, and means for guiding said belts during said upper traverse in such a path that opposed areas thereof are gradually disposed at an increasing angle with respect to the plane of the deck until the angle between the belts becomes sufficiently acute that one belt will exert pressure at the edge of an article being faced and the other belt will exert pressure on the article inward from the edge, and means for causing said belts gradually again to assume a position substantially parallel to the deck.

8. A facing machine for articles having a flat face having, in combination, endless conveyor means substantially flat at each end of

- its active run, means for driving the conveyor, means for supplying the articles to be faced to one end of the conveyor, means intermediate the ends of the conveyor for causing the sides of the conveyor to be progressively tilted toward each other to form an acute angle, and means for adjusting the tilting means so that at the point of greatest tilt the lower edges of the articles will be gripped by the conveyor and their flat faces turned into engagement with the conveyor.
9. A machine for facing articles having a flat face and receding-edge portions, comprising, in combination, endless conveyor means adapted to receive promiscuously disposed article on its upper traverse and to move said articles therewith along its upper traverse, and means to cause the sides of said conveyor to assume along its upper traverse a gradually decreasing angle which at its minimum is sufficiently acute so that the sides of the conveyor adjacent the vertex of the angle will grip the articles at points on opposite sides thereof so as to swing from one side of the conveyor to its other side such articles as are carried flat face upward on either of its sides.
10. A machine for facing articles having a flat face and receding-edge portions, comprising, in combination, endless conveyor means adapted to receive promiscuously disposed articles on its upper traverse and to move said articles therewith along its upper traverse, and means to cause the sides of said conveyor to assume along its upper traverse a gradually decreasing angle which at its minimum is sufficiently acute so that the sides of the conveyor adjacent the vertex of the angle will grip the articles at points in different planes on opposite sides thereof so as to swing from one side of the conveyor to its other side such articles as are carried flat face upward on either of its sides, and means to adjust the last mentioned means to varying acute angle positions for the convenient facing of articles of different size.
11. A machine for facing articles having a flat face and receding-edge portions, comprising, in combination, endless conveyor means adapted to receive promiscuously disposed articles on its upper traverse and to move said articles therewith along its upper traverse, means to cause the sides of said conveyor to assume along its upper traverse a gradually decreasing angle which at its minimum is sufficiently acute so that the sides of the conveyor adjacent the vertex of the angle will grip the articles at points on opposite sides thereof so as to swing from one side of the conveyor to its other side such articles as are carried flat face upward on either of its sides, means for delivering articles to be faced to said conveyor and means for carrying the faced articles away from said conveyor.

65 HARRY A. GREENHOLT.
